UNITED STATES PATENT OFFICE.

IRWIN LEWIS CATON, OF ASHEVILLE, NORTH CAROLINA.

DESK ATTACHMENT FOR TABLES.

1,268,926.

Specification of Letters Patent. Patented June 11, 1918.

Application filed May 19, 1917. Serial No. 169,771.

To all whom it may concern:

Be it known that I, IRWIN LEWIS CATON, a citizen of the United States, residing at Asheville, in the county of Buncombe and 5 State of North Carolina, have invented certain new and useful Improvements in Desk Attachments for Tables; and I do hereby declare the following to be a full, clear, and exact description of the invention, such as 10 will enable others skilled in the art to which it appertains to make and use the same.

This invention relates to attachments for tables and has for its primary object to provide an attachment to set on top of an ordinary 15 table, so that the same can be conveniently used, as a desk.

Another object of the invention is the provision of a desk attachment for tables, that consists of a series of drawers and compartments, that can be readily placed or removed from the top surface of a table, so 20 that the table can be either used as a desk or as an ordinary table.

A further object of the invention is the provision of a detachable desk attachment for tables, that consists of a number of independent parts held together in assembled position by removable rods so that the attachment can be readily taken apart for storing or shipping or assembled for use.

A still further object of the invention is the provision of means for arranging the sections forming the desk attachment, so that the same will occupy a very small space.

35 A still further object of the invention is the provision of a desk attachment for tables of the above character that will be simple and durable in construction, and can be manufactured and placed upon the market at a comparatively small cost.

With these and other objects in view, the invention consists in the novel construction, arrangement and formation of parts, as will be hereinafter specifically described, claimed, 45 and illustrated in the accompanying drawings forming a part thereof in which:—

Figure 1 is a perspective view of the improved desk attachment for tables, in assembled position,

50 Fig. 2 is a transverse sectional view through the central portion of the attachment,

Fig. 3 is a rear elevation of the improved desk attachment, showing the two portions forming the rear wall separated, and the different partitions in dotted lines, 55

Fig. 4 is a front elevation of the improved desk attachment in its collapsed form and held in position by the improved binder,

Fig. 5 is a detail perspective view of the improved binder, and

Fig. 6 is a detail sectional view illustrating the connection between the top and side walls.

Referring to the drawings in detail, where- 65 in similar reference numerals designate corresponding parts throughout the several views, the numeral 1 generally indicates the improved desk attachment for a table, which includes the rectangular side walls 2 and 3 70 respectively supporting the rectangular top 4 which is preferably made in one piece and is held in position by detachable rods 5 which extend and frictionally seat in registering apertures 6 formed in the top wall 75 and in the upper edges of the sides 2 and 3. The rods 5 have enlarged heads 7 which limits the inward movement of the same in the apertures and provides means whereby the rods can be conveniently gripped to re- 80 move the same.

A back wall 8 is provided for the top 4 and sides 2 and 3 and consists of an upper portion 9 and a lower portion 10, which is of greater width than the upper portion. The 85 upper portion 9 has formed therein a series of apertures 11 which are positioned adjacent the upper and side edges of the same and register with openings formed in the rear edge of the top 4 and with openings 90 formed in the rear edges of the sides 2 and 3. These registering openings frictionally receive rods 12 which are adapted to hold the upper portion 9 in position. The lower portion 10 of the back 8 is likewise provided 95 with recesses 13 positioned adjacent the side edges thereof, which register with openings formed in the rear edges of the sides, and the registering openings receive removable rods 14 which hold the lower portion in position. 100

A partition 15 is spaced from the top 4 and is held in position by rods 16 extending through apertures formed in the side and

rear edges of the partition registering with apertures formed in the side walls 2 and 3 and in the upper portion 9 of the rear wall 8. The partition 15 forms the lower wall for the pigeon holes 17 which are formed by a series of spaced vertical partitions 18, which engage the lower surface of the top 4 and the upper surface of the partition 15 and the inner face of the upper section 9 of the back wall 8. The vertical partitions 18 are held in position by detachable rods 19 positioned in apertures formed in the table top 4 and the upper section 9 of the rear wall 8 registering with apertures formed in the upper and rear edges of the vertical partitions.

A pair of spaced upright partitions 20 are positioned in spaced relation and parallel with the side walls 2 and 3 and may extend back into engagement with the upper and lower sections 9 and 10 of the rear wall 8 and are detachably secured thereto by rods 21 extending through registering apertures formed in the rear edges of the upright partitions 20 and the upper and lower sections 9 and 10 of the rear wall 8 and held against relative forward and rearward movement by removable rods 22 positioned in registering apertures formed in the upper edge of the upright partitions 20 and in the partition 15 of the pigeon holes 17.

A pair of spaced horizontal partitions 23 are arranged between the upright partitions 20 and the side walls 2 and 3 respectively. The lower partition of the pairs of partitions 23 extend flush with the lower edge of the upright partitions 20, while the upper of the pairs of horizontal partitions are spaced from the upper edge of the upright partitions 20 and the floor 15 of the pigeon holes. The horizontal partitions 23 are held in position by means of removable rods 24 extending through registering apertures formed in the side walls 2 and 3 and through registering apertures formed in the upright partitions 20 and the outer edges of the upright partitions and inner side edge of the horizontal partitions and through registering apertures formed in the rear edge of the lower section 10 of the rear wall 8. The upright partitions 20 and the horizontal partitions 23 and the side walls 2 and 3 and the floor 15 of the pigeon holes 17 define openings for the drawers 25. The horizontal partitions 23 form supports for the drawers 25.

A shelf 26 is secured between the upright partitions 20 by means of rods 27 which extend through registering apertures formed in the lower section of the rear wall adjacent the upper edge thereof and in the rear edge of the shelf.

All of the rods 5, 12, 14, 16, 19, 21, 22, 24

and 27 are identical in construction with each other and each is provided with the enlarged head as previously described.

The sections of the desk attachment 1 are so formed and the proportions of the same are so arranged in relation to each other that when the desk attachment is taken apart the sections can be readily placed together, so as to occupy a minimum amount of space, as is clearly illustrated in Fig. 4. In this figure the back section 10 is placed to form the lower layer, the top 4 is positioned to form the second layer, the sides 2 and 3 and the horizontal partitions 23 and vertical partitions 18 are placed to form the third and fourth layers. The shelf 26 and the upright partitions are positioned to form the fifth layer, the floor 15 of the pigeon holes is sufficient to form the sixth layer, the upper back section 9 is positioned to form the seventh layer, and the drawers are turned upside down in position to form the top layer, and the removable rods are positioned under one of the drawers.

A binder 28 is provided for holding all of the sections in folded position and consists of two independent sections 29 fastened together by flexible straps 30. Each section 29 consists of a pair of spaced upright bars 31 connected at their lower portions by means of hinges 32 to a horizontal bar 33. One of the upright bars 31 is connected at its upper portion to a bar 34 by means of a hinge 35. The free end of the upper horizontal bar and the free ends of the upright bars 31 are connected together by the ordinary hasp fasteners 36.

In use the approved attachment is assembled in the above described manner and the same is then placed in position upon the top of an ordinary table (not shown) and the same used as a desk. The series of drawers, shelves, and pigeon holes form convenient means for the reception of paper, pens, pencils, etc.

In practice I have found that the form of my invention illustrated in the accompanying drawings and referred to in the above description, as the preferred embodiment, is the most efficient and practical; yet realizing the conditions concurrent with the adoption of my device will necessarily vary, I desire to emphasize the fact that various minor changes in details of construction, proportion and arrangement of parts may be resorted to, when required without sacrificing any of the advantages of my invention as set forth.

What is claimed is:

A take down desk top for tables comprising a plurality of independent sections consisting of a top wall, a two part rear wall, side walls, vertical and horizontal partitions,

arranged between the walls, said walls and partitions having a plurality of registering apertures formed therein and removable fastening rods adapted to frictionally seat in
5 said registering apertures to hold the walls and partitions in position, as and for the purpose specified.

In testimony whereof I affix my signature in presence of two witnesses.

IRWIN LEWIS CATON.
